UNITED STATES PATENT OFFICE.

GOTTLOB F. HONOLD, OF SHEBOYGAN, WISCONSIN.

UNDERTAKER'S FLOWER-DISPLAY STAND.

1,115,673.

Specification of Letters Patent.

Patented Nov. 3, 1914.

Application filed February 6, 1913. Serial No. 746,487.

To all whom it may concern:

Be it known that I, GOTTLB F. HONOLD, a citizen of the United States, and resident of Sheboygan, in the county of Sheboygan 5 and State of Wisconsin, have invented new and useful Improvements in Undertakers' Flower-Display Stands, of which the following is a description, reference being had to the accompanying drawings, which are a 10 part of this specification.

This invention relates to improvements in undertakers' flower display stands.

At funerals it is the usual custom to arrange the flowers received on the casket and 15 around the room on any convenient article of furniture. This arrangement does not show the flowers to the best advantage on account of not being banked or placed at an angle, and in some cases the flowers thus arranged occupy considerable more space than 20 is desired.

It is one of the objects of the present invention to provide an undertaker's flower display stand which will overcome the above 25 mentioned objectionable features and which is adapted to hold and display flowers to the best advantage and which may be adjusted to any angle and arranged around the casket in any manner desired.

30 A further object of the present invention is to provide an undertaker's flower display stand having means for securing the flowers to the stand and also for arranging the flowers on the stand in any manner desired.

35 A further object of the invention is to provide an undertaker's flower display stand so constructed that two or more of the stands may be easily clamped together to form a continuous support for a long bank of 40 flowers.

45 A further object of the invention is to provide an undertaker's flower display stand of simple construction and which may be folded to occupy a minimum space for convenience of transportation.

With the above and other objects in view, the invention consists of the improved undertaker's flower display stand and its parts and combinations as set forth in the claims, 50 and all equivalents thereof.

In the accompanying drawings in which the same reference characters indicate the same parts in all of the views: Figure 1 is 55 a front view of one of the complete stands and a fragment of another stand connected

thereto; Fig. 2 is a side edge view thereof; Fig. 3 is a rear view of a fragment of the flower holding portion of the stand removed from its support; Fig. 4 is a vertical sectional view taken on line 4—4 of Fig. 3; 60 Fig. 5 is a transverse sectional view taken on line 5—5 of Fig. 4 with the flower holder positioned at right angles to the upright portion of the stand; Fig. 6 is a vertical sectional detail view of a fragment of the 65 flower holder; Fig. 7 is a detail view in folded position of the flower holder frame; and Fig. 8 is a detail view of one of the latches.

Referring to the drawings the numeral 70 10 indicates the telescoping standard having diverging hinged legs 11 which may be folded closely against the side of the standard when not in use. The legs at their upper ends are hinged to the collar 12 adjustably mounted on the standard and also have a medial connection with the standard by means of the links 13 and the collar 14. This last mentioned collar is also adjustably 75 mounted on the standard and serves in connection with the links to hold the legs in expanded or open position. The adjustability of the collars also provides for adjusting the height of the stand in addition to the adjustability provided by the telescopic standard 10. In adjusting the upper member 15 of the telescopic standard a thumb nut 16 threaded through the upper end of the lower member 17 impinges 80 against the said upper member and securely 90 binds the two parts together in adjusted position.

The upper end of the upper member is provided with a T-head 18 which fits into the curved recessed portion 19 of the brace 95 member 20 forming part of the flower holding frame 21. The curved recessed portion has a slot 22 through which the flattened portion 23 of the upper member extends to provide for the T-head engagement with the 100 inner curved wall 24 of the said portion 19. The outer concentric surface of the portion 19 is provided with transverse serrations 25 which are engaged by a serrated washer 26 carried by the upper member 17 and clamped 105 to the serrated curved wall of the brace member 20 by a thumb nut 27 threaded on the upper member 15. By threading the nut upwardly the serrated washer engages the serrated wall and the T-head is clamped 110

against the inner curved wall of the brace member 20 and the parts are thus firmly clamped together in adjusted position.

To permit the easy separation of the upper member 15 from the brace member 20, the curved recessed portion 19 is provided with a transverse slot 28 extending across the slot 22 which is of sufficient size to permit the T-head being passed therethrough edgewise when the holder frame is tilted to a plane parallel with the upper member 15 and the thumb nut is threaded downwardly on the member to permit the separation of the parts.

15 The brace member 20 is of elongated form and its opposite ends are provided with segmental portions 29 which turn into engagement with and between the segmental ears 30 and the back portion of the flower holding frame 21. The ears are formed of spring metal and have their entrance ends 31 slightly bent toward the holder 20 to lock the parts together when the brace frame is snapped into engagement therewith.

25 The flower holding frame 21 is formed of a pair of rectangular pieces of sheet metal 32 reinforced along their front side edges by angled strips 33, and the adjacent edge portions of the two sections are connected together by hinges 34 which permit the said sections being folded forwardly toward each other. The rectangular plates of sheet metal 35 forming part of the flower holding frame 21 are provided with perforations 36 and 30 with tongues 37 projecting forwardly and upwardly from the perforated portions of the plates. Stems of flowers placed between the tongues and the plates will be securely held in place and as the tongues are comparatively close together the flowers may be arranged in the form of a bank and in arranging them in this form the flower stems may also be stuck through the perforated portions of the plates to make a solid bank.

45 In order to connect several of the supports together to form a long continuous bank the side angled strips 33 on one side of each frame are provided with latches 38 having bent over end portions 39 which loop over 50 the adjacent portions of the angled strips and securely lock them together.

From the foregoing description it will be seen that the display stand is of very simple construction and is well adapted for the 55 purpose described.

What I claim as my invention is:

1. A flower display stand, comprising a support, a brace member connected thereto, a two-part-hinged-together holder carried 60 by the brace member, said brace member extending transversely across the hinge joint of the holder and serving to lock the holder in open position, and means forming part of the holder for attaching flowers thereto.

65 2. A flower display stand, comprising a

support having an upper threaded portion and a T-shaped head, a brace member having a curved recessed portion which is engaged by the T-shaped head, a clamping nut threaded on the upper portion of the support and engaging the curved recessed portion of the brace member, a two-part-hinged-together holder removably carried by the brace member, said brace member serving to lock the two portions of the holder in open position, and means forming part of the holder for attaching flowers thereto. 70 75

80 3. A flower display stand, comprising a support having an upper threaded portion and a T-shaped head, a brace member having a curved recessed portion which is engaged by the T-shaped head, a clamping nut threaded on the upper portion of the support and engaging the curved recessed portion of the brace member, a two-part-hinged-together holder removably carried by the brace member, said brace member serving to lock the two portions of the holder in open position, means forming part of the holder for attaching flowers thereto, and means for connecting a plurality of the holders together. 85 90

95 4. A flower display stand, comprising a support having an upper threaded portion and a T-shaped head, a brace member having outer segmental ends and a medial curved recessed projection with serrated portions, said projection also having an elongated slot through which the upper end of the support extends with the T-shaped head within the recess, a serrated washer on the upper portion of the support and engaging the serrated portions of the projection, a clamping nut threaded on the support and engaging the washer to clamp the brace member to the support in different angular adjustments, a two-part-hinged-together holder having segmental portions which are engaged by the segmental ends of the brace member, said holder provided with recessed portions and projecting tongues for holding flowers. 100 105 110

115 5. A flower display stand, comprising a telescopic standard having foldable arms adjustably connected to the lower end thereof and an upper threaded portion and a T-shaped head, a brace member having outer segmental ends and a medial curved recessed projection with serrated portions, said projection also having an elongated slot and a transverse slot intersecting the elongated slot, said elongated slot adapted to receive the upper end of the threaded portion of the standard and the T-shaped head, a serrated washer on the upper portion of the standard and engaging the serrated portions of the projection, a clamping nut threaded on the support and engaging the washer to clamp the brace member to the standard in different angular adjustments, and a two-part-hinged-together holder having segmental portions which are engaged by the seg- 120 125 130

mental ends of the brace member, said holder provided with recessed portions and projecting tongues for holding the flowers.

6. A flower display stand, comprising a support, a brace member adjustably connected to the support and having outer segmental ends, and a two-part-hinged-together holder having segmental portions which are engaged by the segmental ends of 5 the brace member, said brace member extending transversely across the hinge joint 10

of the two part holder and serving to brace the parts in open position, the two part holder being perforated and having projecting means for attaching flowers thereto. 15

In testimony whereof, I affix my signature, in presence of two witnesses.

GOTTLOB F. HONOLD.
